UNITED STATES PATENT OFFICE.

JAMES F. HOBART, OF DETROIT, MICHIGAN, ASSIGNOR TO THE DIAMOND MATCH COMPANY, OF CHICAGO, ILLINOIS, A CORPORATION OF ILLINOIS.

MACHINE FOR PACKING MATCH-BOOKS AND THE LIKE.

1,132,268.

Specification of Letters Patent. Patented Mar. 16, 1915.

Application filed April 9, 1914. Serial No. 830,712.

To all whom it may concern:

Be it known that I, JAMES F. HOBART, a citizen of the United States, and resident of Detroit, in the county of Wayne and State of Michigan, formerly of Barberton, in the county of Summit, State of Ohio, have invented certain new and useful Improvements in Machines for Packing Match-Books and the like, of which the following is a specification.

This invention relates to a machine for packing book or card matches and the like; the same being especially, through not exclusively, designed for use in connection with the match-book making machine set out in Letters Patent of the United States No. 1,042,472, dated October 29, 1912, to which reference may be had. In the said patented machine match-books, wedge-like or tapering in form (owing to the presence of match heads of the covered cards or splints) are produced, and thence discharged in succeeding pairs with their larger ends rearward; and accordingly the machine herein illustrated as embodying my invention, is designed to receive the books as rapidly as they are thus discharged and to pack them in predetermined quantities, uniformly and compactly, in suitable boxes or containers, in such a manner that each box will contain two layers of match books with a wide partition strip between them, and each layer will comprise two orderly rows of match-books with a narrow partition strip between them.

The invention comprises various novel features of construction and organization, and principles of operation, which will be hereinafter particularly described and claimed; it being understood that the invention is not limited to use with the particular articles illustrated, nor is it confined to the specific structural details shown and described.

In the drawings—Figure 1 is an end elevation of a packing machine embodying a form of my invention adapted to the packing of tapering match-books, a portion of the match-book making machine being shown. Fig. 2 is a side elevation, partially in section, of the packing machine. Fig. 3 is an end elevation of the pocketed book reverse wheel and its immediate connections, a book of a pair being represented as contained within and positioned by the wheel

preparatory to the transference of the pair of books to the selecting mechanism. In this view is represented one of the next succeeding pair of books before their entrance to the opposing pocket of the wheel. Fig. 4 is a rear elevation, partly in section, of the mechanism illustrated in Fig. 3. Fig. 5 is a sectional detail, partly in elevation, of the reverse wheel and mechanism associated therewith for transferring the contained books from said wheel to the selecting and assembling mechanisms. In this view is illustrated a receptacle into which odd or rejected books drop by gravity from the selecting mechanism. Fig. 6 is a longitudinal section, partly in elevation, illustrating the book selecting mechanism and adjacent parts of the plunger devices for pushing the books into the assembling chambers. In this view the various parts are illustrated in their normal position whereby a pair of books ejected from the reverse wheel will be held in front of the respective assembling chambers but if a single book be ejected it will be discarded. Fig. 7 is a similar view of the right hand portion of the mechanism illustrated in Fig. 6, showing the relative position of the parts when a pair of books is discharged from the reverse wheel. Fig. 8 is a view similar to Fig. 7 showing the action of a pair of books upon the selecting devices in the progress of the books within the assembling chambers. Fig. 9 is a similar view showing the action of the selecting mechanism when a single book is discharged from the reverse wheel. Fig. 10 is a view similar to Fig. 8 showing the relative position of the parts when the assembling plungers are at the limit of their rearward or feeding stroke. Fig. 11 is a transverse vertical section, as on the line 11—11 of Fig. 6. Fig. 12 is a fragmentary plan, partly in section, showing the devices for controlling the selecting mechanism, the vertical book-guides, and adjuncts. Figs. 13 and 14 are details of the cam-slotted ends of the respective vibratory controlling bars of the said devices. Fig. 15 is an elevation of a slotted supporting bracket for the actuating levers for said bars. Fig. 16 is a longitudinal vertical section through a part of the assembling chambers, showing the vertical book guides; the feed-plungers; the lateral guide plates for the books, and the back-stop therefor. In this view upper and lower

rows of books are represented and also the narrow-partition strip as supported directly above the lower row. Fig. 17 is a horizontal section, as on the line 17—17 of Fig. 16. Fig. 18 is a longitudinal vertical section, partly in elevation, through the assembling chambers and their associated parts, showing the book back-stop as retracted to its forward position preparatory to the initial feeding of the books to the chambers, and showing also the actuating and controlling devices, including the counting gear mechanism, for said stop. Fig. 19 is a similar view showing each of the chambers as supplied with its full quota of books, and the several parts in the relative positions which they occupy at that juncture. Fig. 20 is a detail, in side elevation, of the counting gearing, showing the parts in the positions which they occupy during the progress of counting and assembling the match books. Fig. 21 is an end view of said gearing. Fig. 22 is a rear elevation, partly in section, of Fig. 18, showing more clearly the yielding connections whereby the book back-stop is maintained against the books within the assembling chambers. Fig. 23 is a side elevation of the reciprocating carriage for supporting and actuating the book-assembling plungers, showing the latch dogs on said carriage, the vibratory controlling bars therefor, and adjuncts. Fig. 23^a is a sectional detail showing the adjustable mounting of said carriage on the reciprocating frame. Fig. 24 is a partial side elevation of the machine, showing the narrow and wide strip magazines, the devices for ejecting the respective strips periodically therefrom, and associated mechanisms. In this view the narrow strip slide is illustrated in position to eject a narrow strip, and a wide strip, previously ejected, is positioned in front of a pocketed temporary holder and in the path of plunger devices by means of which two columns of books, with a narrow strip between them, plus the opposing wide strip, are forced into said holder. In this view certain parts are represented as broken away to expose features otherwise concealed. Fig. 25 is a similar elevation showing the positions of the parts after the match books and strips have been introduced to the temporary holder. Fig. 26 is an elevation of the outer end of the wide-strip feeding magazine, showing the plunger and the devices for stopping the feeding of strips during alternate downward strokes of said plunger. Fig. 27 is a partial vertical section through the end wall of the magazine, as on the line 27—27 of Fig. 26. Fig. 28 is a side elevation, partly in section, of the temporary holder; the box carrier below the same; the mechanism for transferring the contents of the said holder to the boxes in the carrier; the mechanism for feeding

empty boxes to and discharging filled boxes from said carrier, and adjuncts. Fig. 29 is a plan of the temporary holder, the adjacent box magazine, the plunger mechanism for feeding the empty boxes to the carrier beneath said holder, and a part of the conveyor belt for removing the filled boxes. Fig. 30 is a side elevation, partly in section, of the temporary holder and the box carrier, showing the train of gearing connecting said holder and carrier. Fig. 31 is an edge view of the said gear train. Fig. 32 is a detail of drive and lock gears included in said train.

The discharging end of the book-match machine with which my packing apparatus is associated is represented in a general way in Fig. 1, wherein 60 indicates an intermittently-rotatable pocketed wheel, from which the books (a) are discharged in pairs, larger or headed ends rearward, upon a yielding supporting plate 61 by the action of the ejecting arms 62 of a reciprocating frame 63; and 64 indicates reciprocating fingers by means of which the free ends of the cover flaps of the books are tucked under the stapled end folds of the covers. When the tucking operation has been completed and the fingers leave the finished books, the latter are pushed rearwardly, abreast, by the next succeeding pair of books, and so on.

The packing apparatus is located directly in rear of the book-match machine, and is adapted to receive the finished books, pair by pair, as rapidly as they are discharged from the latter.

The main supporting frame-work of the packing apparatus, in the form shown, includes a base 65 and two or more superposed frames 66, 67 sustaining a bed plate 69; a middle or partition plate 70 and an upper plate 71 being supported above the bed-plate 69 by suitably-located lugs and brackets.

Adjacent the delivery portion of the book-match machine is an oscillatory member, termed a reverse wheel, which is mounted to rotate in a bracket 72 on the plate 71. This reverse wheel comprises a centrally-grooved head or body 73 from the sides of which project a series of relatively spaced ribs 74 which provide on each side of the head two diametrical intersecting chambers at right angles to each other. The chambers on one side of the head are in alignment with the corresponding chambers on the other side, and these chambers are so located that in each oscillatory stroke of the head a pair of corresponding chambers are positioned to receive a pair of books from the match book machine; each pair of books as they are being discharged from the latter pushing the immediately preceding pair into the opposing chambers of the reverse wheel. When a pair of books have thus been entered there-

in the reverse wheel is moved a quarter-turn on its axis thus directing the contained books from a horizontal to a vertical position, with the larger or headed ends of the matches pointing upward or downward according to the direction of the stroke of the wheel, so that the books thus disposed may be ejected downward from the member. (See Figs. 3 and 4).

10 While any suitable means for oscillating the reverse wheel may be employed, I have devised and prefer to use for this purpose devices actuated by and under the influence of the reciprocating ejecting frame 63 of 15 the match-book machine.

Referring to Figs. 3 and 4, 75 designates a vertically-disposed channeled head carried by a rearward extension of the frame 63 and reciprocable thereby toward and from 20 the rear of the reverse wheel. On the head are arranged in spaced relation to each other two inwardly-projecting socketed portions 76, 77 which are formed on blocks 78, 79 respectively, slidably fitted to the vertical channel or groove of the head. The 25 blocks are provided with pins or screws 79 which extend through vertical guide slots 80 in the end of the head and are united to by means of a spring 81, which tends to 30 draw the blocks and the portions 76, 77 yieldingly toward each other. These portions constitute in effect yielding dogs which are adapted in their horizontal reciproca- 35 tion to act in alternation upon the opposing members 82, 83 respectively, of a rock-lever 84. This lever is carried by the outer end of a shaft 85 which is journaled in a bearing in the bracket 72. The inner end of the shaft has affixed thereto a crank 86 the 40 oscillation of which, through the action of the rock-lever, is limited to about 90 degrees by the contact of stop shoulders 87, 88 on the crank and bracket-bearing respectively. The crank is pivotally connected 45 with the grooved body 73 of the wheel, near the periphery of the latter, by means of a rod 89, whereby the wheel is timely oscillated by the action of the crank. The outward movement of the ejecting frame 63 50 carries the head 75 to the position indicated by the dotted lines, and the return movement to the position indicated by the full lines in Fig. 3. The relative positions of the parts are such that in the return 55 movement of the frame, the lower dog 77 engages and advances the opposing lower member of the rock-lever, thus by actuation of the crank 86 and rod 89 moving the reverse wheel a quarter-turn and, perforce, 60 bringing the match-books contained in the wheel, to a vertical position, heads uppermost, as seen in Figs. 3 and 4. By mechanism hereinafter described the two books thus positioned by the wheel are depressed 65 therefrom. In the succeeding outward

stroke of the frame 63 another pair of books will be inserted in the opposing pockets or chambers of the wheel, and at the same time the upper dog 76 will ride upon and engage the opposing upper member of the 70 rock-lever. In the succeeding inward stroke of the frame 63 the upper dog 76 will carry the engaged lever member forward, and by actuation of the crank and rod will swing.

75 the reverse wheel back to its previous position and thus bring the contained books to a vertical position, but with the heads downward. By this construction the wheel is oscillated in a manner to receive the successive pairs of books and dispose them al-

ternately in reverse positions as to their larger and thinner ends. It is to be noted that the movement of the reverse wheel is effected during the last half of the return stroke (to the left, Fig. 3) of the recipro- 85

cating book-ejecting frame 63, and that during the outward stroke of the latter the lower dog moves away from the proximate arm of the rock lever, and the inclined under surface of the upper dog impinges 90

against the opposing upper limb of said lever, slides easily over the same and snaps into engagement therewith. It is also to be noted that during the inward stroke of the 95

said ejecting frame the inactive dog freely passes the proximate limb of the lever, owing to the outer position of such limb as it approaches the vertical in its travel. Further, that the reverse wheel is effectually locked at the end of each of its movements 100 by the engagement of the rock-lever with one of the dogs, in conjunction with the co-action of the opposing shoulders 87, 88 on the crank and bearing bracket respectively.

105 The mechanism above referred to for depressing the vertically-disposed match-books from the reverse wheel will now be described, reference being had more especially to Figs. 3 to 5 inclusive. 90, 90 designate two vertically-reciprocating plungers 110

which are guided in tubular posts 91 supported on the main frame adjacent the respective ends of the reverse wheel. These plungers are provided at or near their upper 115 ends with inwardly extending arms 92 which overhang the reverse wheel so as to be movable into and from the vertically-disposed pockets or chambers of the wheel, each arm being of sufficient length to enter the pocket and eject the contained match 120 book downwardly from the reverse wheel.

The inner sides of the posts 91 are slotted for the passage of the arms. The plungers are coupled at their lower end by a yoke 93 (Fig. 5) which is pivotally connected to one 125

end of a bar 94 the opposite end of which is slidably fitted to a bearing collar 95 pivotally mounted on a bracket 96 on the main frame of the book-match machine. The bar 94 is pivotally connected at a suit- 130

able point in its length to a crank 97 on a shaft 98 having its bearings in boxes on the main frame of the packing machine. This shaft 98 bears a pinion 99 in mesh with an intermittently driven spur wheel 100 on the chain drive shaft 101 of the book-match machine. Thus the shaft 98 is actuated and, through the crank connection, the bar 94 is oscillated to effect the vertical reciprocation of the plungers 90. In the present instance the wheel 100 (and its shaft) is actuated to make four equal movements in a rotation, and its diameter relative to that of the pinion 99 is such that the latter is impelled a complete rotation during each quarter-turn of the spur wheel. The bar 94 by virtue of its pivotal and sliding end connections constitutes, in effect, a "floating" member having both vertical and horizontal motion.

The relative arrangement of the bar and the crank 97 is such that a variable motion is imparted to the plungers, the down or ejecting movement starting slowly, increasing rapidly, then diminishing near the end of the stroke. The bracket 96 to which the bearing collar 95 for the bar 94 is pivoted is attached by means of a slot and bolt connection with the frame, so as to be horizontally adjustable lengthwise of the bar and thus provide for a slight vertical adjustment of the stroke of the plungers. The vertically-positioned pockets of the reverse wheel register with openings 102 in the plate 71 in line with vertical book-supporting guides 103 comprising spaced plate members affixed by brackets 103^a to the respective posts 91, (see Figs. 3, 4, 5, 12 and 17,) and hence the books as they are ejected from the wheel are pushed through these openings down into the guides. By reference to Fig. 4 it will be observed that the plunger arms 92 are in different horizontal planes, the right hand arm being higher than the other so that when a pair of books is ejected from the wheel the left-hand book is depressed to a plane below that of the other as indicated in Fig. 6. In Fig. 5 one of the plungers is indicated in its extreme positions of travel, its up or normal position being shown by the dotted lines and its down position by full lines. The plunger arms depress the books in the guides 103 to a position immediately in front of two horizontal chambers 104 where they are yieldingly held by means of devices now to be described.

Referring to Figs. 6 to 11 inclusive, 105, 105 designate two dogs which are pivoted to bearing pieces 107 at or near the front of the respective chambers in position to depend into the paths of the descending books in the guides. These dogs are provided with crank arms 108 to which are pivoted the proximate ends of two parallel rods 109 respectively, the opposite ends of which lat-

ter are pivotally connected by means of a diagonal rod 110. The rods 109 are provided, near their pivotal connections with the rod 110, with adjustable clips 111 which are, in turn, coupled by an extensible spring 112, whereby the dogs are free to swing to and fro as a unit as though their crank arms were connected by means of a direct rod. By this construction it will be seen that when a pair of books is pushed down by the plunger arms, the dogs are concurrently pushed to the right by the books, and thereby by the extension of the spring exert yielding pressure upon the books. Thus the books are securely held within the guides at the mouths of the respective chambers. If, however, a single book only should be depressed from the wheel into the guide way, such book will press the opposing dog rearwardly while the other dog will swing freely in the opposite direction across its guide way. Accordingly the dogs offer no appreciable resistance to the passage of a single book, and the latter, passing freely down its guide-way, falls to the floor or into a suitably disposed receptacle, as 113, Fig. 5. This feature of rejecting single books is an important one, as thereby is prevented a shortage of books in the chambers which are adapted to receive the same in orderly columns of a predetermined number each,—in the present instance twenty-five. It is to be observed that by adjusting the clips 111 more or less along the rods 109 the tension of the spring 112, and therefore the pressure of the dogs upon the books, may be nicely varied as desired. When a pair of books is disposed at the mouths of the respective chambers as above described these books are impelled into the chambers by mechanism of the following description: Arranged to move into each of the guide-ways, directly in front of the chamber 104, is a horizontally reciprocative plunger head 114 against the opposing face of which the book is held by the pressure dog. The plunger head is slotted, as at 115, (Fig. 11) to permit the dog to swing clear thereof during the downward passage of a single book. These heads are carried by horizontal plungers 116 which are affixed to a carriage arm 117 suspended from the book-ejecting frame 63. In the present instance the carriage arm is simply slipped on the frame and is prevented from moving lengthwise of the latter by end collars 118 and interposed thin washers 119, as seen in Figs. 1 and 23^a. Adjustment of the arm longitudinally of the frame, is readily had by transferring one or more of the washers from one side of the arm to the other. The lower end of the arm is provided with a suitably-disposed grooved roller 120 which bears on a track 121 on the bed plate 69, and thereby supports the arm and its connections. (See Fig. 23.)

130

By the above-described construction it will be seen that the plunger heads are actuated concurrently with the book-ejecting frame 63, and hence during each stroke of the latter to discharge a pair of books from the book machine the heads are pushed along the chambers, and in the event of a pair of books being located in the vertical guide-ways, such books will be forced by the plunger heads into the assembling chambers 104. These chambers, one of which is shown in plan in Fig. 17 and both in longitudinal section in Fig. 16, are constituted by the bed plate 69, upper plate 71 and the intermediate partition plate 70. Both these figures represent the books as progressing from the vertical guides to and along their respective chambers, the book indicated at the left of Fig. 17 being located between adjustable side guides whose function is to insure the upright position of the book during its control by and after it leaves the retaining dog, which dog when it is engaged with the book exerts a considerable drag on the upper end of the latter. These guides comprise plates 122 which are adjustably secured, as by means of clamp and set screws 123, 124 respectively, to brackets 125 firmly bolted to the frame plates 69, 71 respectively. The set screws 124 determine the requisite lateral adjustment of the guides relative to the brackets and the clamp screws 123 fix the guides in their positions of adjustment. Each bracket is preferably provided with suitably-disposed bearing lugs 126 for the guides, so as to prevent displacement of the latter even though the screws should be accidentally loosened. By the act of loosening screws 123 of a guide plate such 40 plate may be moved bodily inward and by tightening one or more of the screws 124 any corner, side or end of the plate may be moved inward as required to support the books and yet permit them to move easily along the chamber. The screws are preferably so adjusted that the inner ends of the guide plates are moved very slightly inward as each book is pushed beyond the same by the head-plate, and hence upon the retraction of the latter the book is left standing against the opposing edges of the guides. The books as they are delivered into and assembled within the chambers are prevented from falling by means of a suitable back stop which is 50 mounted and arranged to exert a light predetermined pressure on the upstanding books. This stop recedes as the books accumulate in the chamber, and, as hereinafter described, the stop is automatically and 55 positively drawn backward at the instant a predetermined number of books—in the present instance 25—have been assembled in each chamber. The book stop, in its preferred form, comprises two plates 125¹, one 60 in each chamber, connected by means of arms 126¹, and mounted to travel as a unit in the two chambers. Said stop is held yielding in its inner position against the upstanding books by the following described mechanism: Referring to Figs. 18, 19 and 22, 70 127 is a cord or other flexible connection which is attached to the stop, then led about a horizontal sheave 128 adjacent the receiving end of the chambers, then about a vertically disposed sheave 129 in a laterally-arranged block 130, and then fastened to the partition 70 as at 131 (Fig. 22). To the block is connected one end of a stout retracting spring 132 the other end of which is secured to a bracket 133 on the bed plate 69. By 80 this construction it will be seen that as the books are successively delivered to the chambers the opposing stop is forced back thereby in opposition to the retractive force of the spring. When the predetermined number of books have been assembled within the chambers, the stop 125¹, 126¹ is drawn backward as above mentioned and as hereinafter particularly described, in order to permit the free movement transversely of the chambers of plunger heads 134, 135 (Figs. 17, 24, 85 35) whose function is to discharge the two rows of books from the chamber, as will presently appear. In order that the columns of books shall be suitably guided at their 90 ends during the action of the ejecting plungers thereon guide plates 136 are positioned in proximity to the path of the plunger heads 114 and the stop plates 125¹, respectively, said guide plates being affixed to suitable brackets 137 on the main frame. (See 95 Figs. 17 and 18.) The adjustment of the plunger heads 114 in relation to the adjacent guide plate 136 to compensate for wear, can be readily effected by the connection of 100 the arm 117 with the book-ejecting frame 63 as above-described. The stop-plates 125¹ stand normally about an inch distant from the inner faces of the adjacent forward guide plates 122 as indicated in Fig. 18, but this 105 110 is not sufficient to permit a book or books to fall to the floor of the chamber. The stop plates are limited to this position by means of a chain 138 which is attached thereto, passed about a sheave 139 on a bracket 140 at 115 the outer end of the bed plate, and secured, as by means of a clip 141, to a drum 142 which is loosely mounted on a shaft 143 having its bearings in a suitable bracket 144 on the bed plate. Fast on this shaft 143 is a 120 disk 144^a which is encircled by the rim of the drum and is engaged therewith by an internal lug 144^b which extends from said rim into a peripheral recess 145 in the disk, whereby during the rotation of the shaft and 125 disk, motion is transmitted to the drum. At the beginning of the book assembling action within the chambers the shaft 143 is held rigidly in place, as seen in Fig. 18. This is 130 accomplished by means of a slotted adjust-

able crank 146 fast on the shaft, in conjunction with a connecting rod 147 between said crank and the gear wheel 148 of a counting mechanism hereinafter described. This 5 wheel is intermittently rotated coincident with the delivery of the books to the assembling chamber, and hence the disk is actuated to rotate the drum and wind the chain thereon. Accordingly the back-stop 125¹ is 10 dragged back, step by step, slowly at first, as the crank lies at an acute angle to the rod, then progressively faster as the crank becomes perpendicular to the rod. Then the stop begins to move less at each step, as the 15 crank approaches the end of its travel and forms a very acute angle with the rod. It is for the purpose of compensating for this variable motion that the one inch of non-travel for the back stop is provided, as above 20 mentioned, and it may be noted, in passing, that it is immaterial whether the books get ahead of the stop or the stop advances ahead of the books during the assembling operation, for there is but one inch difference at 25 the start, and the mechanism is so timed that the stop is brought into alignment with the rearward guide 136 when the predetermined number of books have been assembled in the chambers. (See Fig. 19.) The chain 138 is 30 at all times under tension through the action of a helical spring 149, (Figs. 18 and 22) one end of which is secured to the drum and the other end to a collar 150 fast on the shaft 143, but as this spring is weak compared 35 with the retracting spring 132 the back-stop is at all times under the superior force of the latter. The office of the spring 149 is to keep the chain wound upon the drum 142, or as much of the chain as may at 40 any time be let loose by the sudden reverse movement of the crank 146, which takes place immediately after each counting action by the gear 148. The peripheral recess 145 in the disk is sufficient to permit independent rotation of the drum in an arc of 45 about 100 degrees, except for the tension of the spring 149 and the pull of the chain as above described. Thus the movement of the back stop 125¹ is limited at each end by 50 the length of the recess in the disk. Said stop does not align with the rearward guide 136 when the stop is at the outermost limit of its travel. Instead it moves very slightly past and then moves inward again and aligns 55 with said guide 136 as represented in Fig. 19. The function of the counting mechanism above referred to is to insure the assembling of a predetermined number of match books within each of the chambers, before 60 the books are ejected from the latter, and this even though single books should be delivered to the reverse wheel and rejected as above explained. This mechanism, in its preferred form, I shall now proceed to describe, reference being had more especially 65 to Figs. 11 to 15, inclusive, Figs. 18 to 21, inclusive, and Fig. 23, of the drawings: The intermittently-rotatable gear 148 from which motion is transmitted to the winding drum as above-described, is mounted on a 70 shaft 151 having its bearings in brackets on the main frame. This gear, which is a mutilated gear having a prescribed number of teeth, has affixed thereto a counting segment 152 having in the present instance twenty- 75 five teeth with which mesh the laterally projecting pins 153—four in the present instance—of a pin wheel 154. This pin wheel is fast on a stud shaft 155 having its bearings in a bracket on the main frame. Fast 80 on the stud shaft is another pin disk 156 having four projecting pins 157 with which are adapted to engage under normal conditions during each active stroke of the reciprocating arm 117 a pivoted dog 158 on an 85 extension of said arm, thereby intermittently rotating the pin wheels as a unit and correspondingly actuating the segment 152 and gear 148. By normal conditions is meant when there are two match books in 90 position to be advanced into the assembling chambers. Otherwise the dog is positioned to escape the pin wheel, and hence the latter is unaffected thereby as will presently appear. The pin wheels are automatically 95 locked against movement in either direction by means of a segmental head 159 which is pivoted to swing by gravity into the space between two of the pins 157. The lock is moved out of engagement with the said pins 100 by the action of the pivoted dog 158 as the latter approaches the pin wheels; the lock being provided with a lateral projection 159^a against which the dog impinges and thus pushes the lock bodily beyond the opposing 105 pin 157 and releases the pin wheels sufficiently to permit their impulse by the contacting dog 158—that is, to the right. The pin wheels, however, are still locked against backward movement by the continued contact of the lock and the rearward pin 157. During the retrograde or idle movement of the dog 158 the lock 159 drops back by gravity, thus reengaging two succeeding pins 157 and again locking the pin wheels and 110 their adjuncts. In each impulse of the pin wheels the counting segment 152 and gear 148 are advanced one step coincident with the delivery of one pair of match books to the assembling chambers. Fast on the shaft 115 151 is a mutilated gear 160 similar to the gear 148, with the teeth of which former is adapted to mesh the pinion 99 on the shaft 98. Thus motion is transmitted to the gear 160 when the toothed portion thereof is in 120 mesh with the pinion. A similar pinion 161 mounted on a suitably-disposed shaft 162 is adapted to mesh with the teeth of the gear 148, and hence during the rotation of the latter, when its teeth are in mesh with the 125 130

gear 148, said pinion 161 is rotated. The ratio of the gear wheels and the relative disposition of the blank spaces of the mutilated wheels 148, 160 are such, that each twenty-fifth movement of the chain drive shaft 101 (which makes one-quarter turn in its rotation as above mentioned) is transmitted to the shaft 151; or in other words, this shaft 151 remains idle during twenty-four impulses or movements of the shaft 101 but makes one complete rotation during the twenty-fifth impulse. The idle periods are utilized for counting out the prescribed number of books for each assembling chamber, the twenty-fifth book being counted upon the impulse which revolves shaft 151. This condition occurs in each twenty-fifth impulse of the gear 99 provided twenty-five books have been deposited in each chamber. Failing to receive the necessary number of books the counting gears do not advance the gear 160 into mesh with the pinion 99, and consequently no impulse is transmitted to the shaft 151 from the pinion 99 until twenty-five books have been counted into each chamber, even though single books have been coming down continually and the pinion 99 has been making regular rotations. Fig. 18 shows the relative positions of the gears immediately after an impulse has been transmitted therethrough from the pinion 99 to pinion 161. It will be noted that the mechanism is rigidly and positively locked in position, the first tooth of counting segment 152 being in contact with a pin 153 of the pin wheel 156, the last tooth of gear 148 being in contact with one of the teeth of the pinion 161, and the last tooth of gear 160 being in contact with a tooth of pinion 99. Furthermore, the pinion 161 is also locked against the gear 148 by means of a Geneva stop movement, comprising a concave member 162^a on the pinion bearing against a plain faced segment 163 on the gear 148; said segment being preferably provided at its respective ends with renewable wear surfaces 164, 165. From the foregoing it will be seen that the pinion 161 and its shaft are unable to rotate in either direction until such time as the mutilated gears 148, 160 shall have advanced twenty-five teeth and are ready to transmit an impulse from pinion 99 to pinion 161. A succeeding impact of the reciprocating dog 158 with the pin wheel advances the counting segment 152 one tooth and correspondingly impels the mutilated gears 148, 160, thus freeing the end teeth of the latter from the pinions 161, 99, respectively. At this juncture the pinion 99 makes a complete rotation, but being entirely disconnected from the gears 148, 160, no movement of shaft 161 can take place, even though it were not rigidly held by the Geneva stop. Fig. 20 shows the relative positions of the gears during the

progress of the counting operation. As therein indicated the gear 161 is locked against movement in each direction by the Geneva stop, which also acts as a starter; the teeth of the counting gears 148, 160 are free from their respective pinions, and the entire counting mechanism is in contact with and under the control of the pin wheel devices which thus intermittently feed and lock said mechanism until twenty-five books have been counted into each assembling chamber. Fig. 19 shows the relative positions of the gearing when the counting is completed. As therein illustrated the pin wheel has moved the last tooth of counting segment 152 into a position where the segment is entirely past all the counting pins and is thus free to move. The first tooth of the gear 160 has been brought into contact with the pinion 99 and is ready for movement during the next quarter rotation of the chain-drive gear 100. Suitably-located starters indicated at 164^a and 165^a on gears 99 and 160, respectively, have moved into contact, ready to take the strain from the contacting teeth of gears 99 and 160 during the instant of starting. As will also be observed the gear 148 and pinion 161 have been brought into engagement, the first tooth of the gear 148 being in contact with a tooth of pinion 161, and the starters constituted by the segment end 165 and the opposing projection 162^a of the Geneva stop, being also in position to take the strain of starting from the single contacting gear teeth. During the ensuing rotation of the pinion 99 the parts are returned to the initial or starting position. It is at this period that the sudden reverse movement of the crank 146 occurs as hereinbefore described with reference to the spring-take-up for the retracting chain 138 of the back-stop for the books.

The means for moving the pin-actuating dog 158 to and temporarily maintaining it in inactive position in the event of a single book only being delivered to and from the reverse wheel as previously mentioned, is of the following character, reference being had more especially to Figs. 6 to 15 inclusive: The dog 158 is provided with a laterally extending roller 166 which rests upon two parallel horizontal bars 167, 167^a, which have capacity for vertical movement and thus by their elevation or depression determine the active or inactive plane of the dog in respect to the pin wheel. These bars are pivoted to a suitably disposed bracket 168 on the bed plate and extend side by side toward and beyond the pin wheel, being guided at a suitable point in their length by a vertically slotted bracket 168^a on the bed-plate. The bars are provided at or near their free ends with appropriate cam connections under the control of the book-feeding mecha-

nism as follows: Pivotally mounted within the slotted portion of each of the plunger heads 114 is a U-shaped clip member 169, which is free to swing laterally until it is flush with either side of the head. The clip lies approximately opposite the adjacent pressure dog 105 and as indicated in Fig. 11, the dog is free to swing through the clip as well as through the plunger head.

5 The construction of the parts is such that when a book is caught between a dog and the plunger head, the clip is forced back flush with the face of said head by the pressure of the dog. In Fig. 6 both clips are shown in this position. A pair of vertically disposed rock-shafts 170 are journaled in bearings in the bed plate 69 and upper frame plate 71, each shaft being provided with a lateral projecting tappet arm 171 in the path of the clip, whereby when the latter is pushed back it impinges against the tappet arm and partially turns the shaft. When a single book is ejected from the reverse wheel only one of the vertical shafts 170 is acted upon and the other remains in its normal position, and hence both shafts cannot be acted upon unless there be two books positioned at the mouths of the respective chambers. Each of the shafts 170 is provided near its lower end with a laterally disposed rod or arm 172, and the two arms are so disposed that they extend to and through parallel horizontal slots 173 in a suitably-disposed guide bracket 174 on the bed plate, the longer arm of the outer shaft being deflected to escape the inner shaft 170 (see Fig. 12). These slots 173 guide and support the arms 172 and thus relieve the shafts 170 of the strain to which they would otherwise be subjected. These arms 172 constitute wipers. Their outer extremities extend into cam slots 175, 175^a formed in the two vibratory bars 167, 167^a respectively, the contours of the cam slots being such that when the shafts 170 are oscillated the bars are vertically vibrated relatively to each other. When the shafts are in normal position, as illustrated in Fig. 6, both wipers 172 extend to or adjacent the ends of the respective cam slots, while the tappet arms 171 bear against the opposing clips 169 and hold them in position across the path of any descending books in the vertical guide ways. When the clips, or either of them, are forced back by a book 55 or books, the movement of the clip or clips is imparted to the tappets and their shafts, thus moving the wipers to the opposite ends of their respective cam slots 175, 175^a. Thus the longer wiper moves from *a* to *c* (Fig. 13) and effects by its contact with the intermediate inclined portion *b* downward movement of the bar 167^a, and the other wiper moves from *a* to *c* (Fig. 14) and similarly effects by its contact with the intermediate 60 inclined portion *b* of the cam slot, down- ward movement of the bar 167. The bar 167^a is provided with a relatively large opening 176 to permit the free and unobstructed passage of the shorter wiper. When the shafts 170 are in normal position both vibratory bars are elevated and the pivoted dog 158 is supported and guided by the latter so as to escape the pin-wheel locking head and the pin wheel during the reciprocation of the dog. If two books are delivered to the respective vertical guides the books will act to force back the opposing clips and thus partially turn the respective vertical shafts, thereby effecting the depression of the two bars 167, 167^a to a position 70 wherein they guide and support the pivoted dog in its active path and insure its impingement against the lock to release the pin wheel and then against the pin-wheel to impel the latter and the counting segment 75 152. If no books be delivered to the vertical guides the shafts and bars will, of course, remain in their normal positions and no counting will be effected. If, however, a single book is delivered to either of the 80 guides the opposing clip will be forced back to turn the proximate shaft and effect the depression of the bar which is connected with the latter, but the other clip, shaft and bar will be unaffected, and hence the latter 85 bar will support the pivoted dog in an idle path. From the foregoing it will be seen that the dog is permitted to assume its active position and the counting mechanism is operated when and only when two match books 90 are delivered from the reverse wheel to the respective vertical guides. The bars 167, 167^a are automatically and positively reset to their normal or raised position in each rearward or active stroke of the assembling 95 plunger. This result is efficiently accomplished by means of two projecting lugs 177 which are affixed to or formed on the carriage arm 117 in alignment with the tappet arms 171 of the respective shafts 170 so as 100 to impinge against said arms 171 as the carriage arm approaches and reaches the end of its travel, and this whether the shafts 170 are in their normal or in their shifted positions. This construction obviates any 105 liability of accidental unlocking of the controlling bars 167, 167^a when a pair of books have not been delivered to the two guide-ways. When the two rows of match books have been counted and assembled in their 110 respective chambers as above described, they are ejected therefrom in superposed columns into a pocketed temporary holder to be hereinafter explained, a narrow partition strip 178, which has previously been fed to and 115 supported by end clips 179 beneath the partition and directly above the lower column, being pushed with and between the columns into said holder. Rows of match books thus 120 partitioned are delivered to successive pock- 125 130

ets of the temporary holder, and each alternate charge has associated therewith a wide partition strip 180, so that when the contents of two pockets are successively delivered to a box or carton the latter contains two superposed layers of match books with an intervening partition strip, each layer comprising two rows of match books with a narrow partition strip between them. 10 Means for supplying the narrow strips to successive pairs of rows and the wide strips to alternate pairs of rows of match books will be presently described.

As previously mentioned the column ejecting mechanism includes two plunger heads 134, 135, movable transversely within the respective chambers. (See Figs. 17, 24 and 25.) The lower plunger head 134 is carried by rods 181 which are affixed to a bracket 182 bolted or otherwise firmly secured to a horizontally reciprocable slide plate 183. This slide is connected by means of a link 184 to the upper end of a rock lever 185 which is fulcrumed in a bracket 186 on the main frame. (See Figs. 1 and 2.) The bearing sleeve of this lever is equipped with an arm 185¹ which is connected by means of a pin or roll 187 with a peripherally grooved cam 188 fast on the shaft 162 hereinbefore described with reference to the counting mechanism, the contour of the cam being such as to effect the timely reciprocation of the slide. Upon the counting and assembling of twenty-five books in each chamber the shaft 98 makes a complete rotation as previously explained, and it is therefore during this period that the cam 188 and its connections are actuated. When the forward impulse is imparted to the slide 40 183, the plunger head 134 is driven forward and the opposing column of books, with the narrow partition strip, is thus pushed transversely of the chamber.

The upper plunger head 135 is carried by rods 189 which extend slidingly through a stationary bracket 189^a and are affixed to a bracket 190 slidingly mounted on the rods 181 of the lower plunger head, whereby is secured a timely movement of the lower plunger to effect the disposition of the lower column of books and the narrow partition strip beneath the upper column, before the upper plunger head acts upon the latter, and thus the two columns with the interposed strip are simultaneously ejected from their respective chambers. The adjustment of the throw of the plunger heads is conveniently effected by slightly moving cam 188 upon shaft 162, thin washers, for example, being placed between the cam and the end of the adjacent bearing.

The ends of the plunger heads 134, 135 are illustrated as provided with elongated flanges 191 which are adapted, during the active movement of the heads, to contact

with and hold back the stop 125¹, 126¹. This retention of the stop is effected during the action of the plungers because the stop is released by the chain 138 the instant the advance movement of the said plungers begins. 70 The release movement of the stop is very slow and the plunger movement quick, and hence the plunger head flanges 191 are moved behind the stop before the latter can pass to the path of the plunger heads. During the advance of said plunger heads the flange of the lower head passes behind the proximate stop plate 125¹ and sustains the stop in position until that head has moved into line with the upper plunger head. 75 Then the latter plunger head, as the two heads proceed, passes in behind and sustains the stop. During the return movement of both plunger heads the elongated flange 191 of the upper head sustains the proximate stop plate in the entire movement because such head does not begin its return motion until the other plunger has moved backward against the slide bracket 190. Thereupon further movement of the slide 183 causes 80 both plunger heads to move back together. The flange of the lower plunger head 134 is useful only during the first portion of the forward movement of that head, since the flange of the other plunger head sustains the stop during the remaining forward and the entire return movement of both plungers as just described. 95

It is to be noted that both plunger heads 134, 135 are firmly locked at the end of their forward movement by the slide bracket 190 abutting against the stationary bracket 189^a and being there securely held by the action against the bracket 190 of the bracket 182 on the slide plate 183 previously described. 100 (See Fig. 25.) Also that the plunger heads 134, 135 are held in their retracted position by a reversal of the operation just described, that is to say, the plunger 135 is held against the stationary bracket 189^a by the slide 110 bracket 190, and the latter bracket is maintained in position by the plunger head 134. (See Fig. 24.)

The narrow partition strips 178 are contained in a magazine 193 which is suitably supported on the main frame in a vertical position directly above the reciprocating slide 183, the latter being provided on its upper surface with a transverse bar or ledge 194 which in the forward movement of the slide engages the lowermost strip and withdraws it from the magazine. The strip is driven under the partition and the ends of the strip engaged and securely held by the clips 179, previously mentioned. The strip 125 is thus held until the two columns of books have been assembled within the chambers. In Fig. 16 a narrow strip is represented as supported at one end by a clip 179, and in Fig. 25, the strip is represented as support- 130

ed on and advanced by the slide to the position where it is sustained by the clips. When the strip is positioned upon the clips the slide 183 is immediately retracted so as 5 to leave the strip 178 in place. In the next succeeding inward stroke of the slide pivoted latches 195 on the lower plunger 134 engage the opposing edge of the strip and advance the latter concurrently with the 10 adjacent row of match books. These latches comprise thin plates pivoted between lugs 196 on the plunger head 134. (See Fig. 17.) In the present instance there are three of these latches in spaced relation to 15 each other, that is, one near each end and one at or near the middle of the strip. At the same time that the strip 178 is carried forward by the latches, another narrow strip is ejected from the magazine 193 by 20 the slide and delivered to the supporting clips. Therefore the latches in their return movement encounter the latter strip, but the latches, being pivoted, tilt and pass idly under said strip. Each latch is pref- 25 erably provided with a beveled tail piece which not only permits the latch to glide freely under the strip but also by its contact with the strip serves as a stop to prevent the undue tilting of the latch. This tail piece 30 also acts as a counterweight to return the latch to its proper position after having passed under a strip.

The wide partition strips 180 are contained in a horizontal magazine 197 suitably 35 supported on the main frame. These strips are disposed, in vertical position, side by side within the magazine 197 and are adapted to be ejected individually therefrom at predetermined intervals by means of a plunger 198 which is reciprocable across the mouth of said magazine in such manner 40 that in each alternate reciprocation a strip 180 is carried directly in front of two partitioned rows or columns of match books 45 which have been advanced into the pocketed temporary holder. The column of vertically-arranged strips within the magazine 197 are normally pressed to the path of the plunger head 198 by means of a follower 50 199 which is arranged to travel within the magazine. This follower is maintained yieldingly against the rear of the column by means of weighted metallic cords 200 which are attached to studs 201 projecting 55 through horizontal slots 202 in the sides of the magazine. These cords are directed about suitably-arranged sheaves 203 on the sides of the magazine 197 and are provided with depending weights 203¹, one of which 60 appears in Fig. 2.

The plunger 198 comprises two vertical bars which are slidingly fitted to vertical guides in the inner face of the end plate 204 of the magazine, the upper ends of the bars 65 being connected by a cross-head 205 and

their lower or acting ends being provided with shoulder pieces 206. These pieces are adapted in alternate downward strokes of the plunger to engage the upper edge of the first or leading strip 180 of the column and depress it to a position directly in front of two partitioned rows of match books preparatory to their entrance into the temporary holder by the plunger heads 134, 135 as above described. (See Figs. 24 and 25.) In the next succeeding action of the said plunger heads the partitioned books without the intervention of a wide partition strip are entered into the temporary holder. 70 75

The plunger cross head 205 is connected by means of rods 207 to the upwardly extending arms 208 of a pair of bell-crank levers fulcrumed on the respective sides of the magazine 197. The downwardly extending arms 209 of these levers are connected by means of links 210 to a bearing block 211 on the slide 183. This block is rigidly fixed to but has provision for limited adjustment lengthwise of the slide. By the connections just described it will be seen that during 90 the horizontal reciprocation of the slide 183 the plunger 198 is vertically reciprocated. 80 85

The alternate feeding action of this plunger 198 upon the wide strips is accomplished as follows: On the end plate 204 (Figs. 26 95 and 27) of the magazine is mounted for movement transversely of said plate a pressure plate 212. This plate is provided with suitably-disposed vertical tongues 213 which are slidingly fitted to guide slots in the 100 magazine end plate 204. These tongues contact with the opposing horizontal strip-column and thus the plate is normally pressed outward by the feeding action of the follower 199 on the column. When the 105 presser plate occupies its normal position the leading strip 180 lies in the path of the shoulder pieces 206 of the plunger and hence a downward movement of the latter will depress such strip as above described. But if 110 the plate 212 be forced inward its tongues 213 will press back all the strips of the horizontal column. Thus the leading strip will be beyond the path of the plunger shoulder and the latter in its reciprocation will not 115 act upon the strip. During alternate reciprocations of the plunger 198 the presser plate is moved inward for the purpose mentioned, as follows: Rotatably mounted on a stud 120 which projects from the end plate 204 through an orifice in the plate 212 is a ratchet wheel 214 which is provided on its inner face with a series of radial corrugations or cam surfaces 215 which co-act with a series of corresponding surfaces 216 on 125 the opposing face of the pressure plate, and thus, in the rotation of the ratchet wheel, press the plate 212 backward toward the strip column or permit it to return to its normal position. A pawl 217 which is held 130

normally engaged with the peripheral teeth of the ratchet-wheel by means of a suitably-disposed spring 218 is pivoted to a rock-lever 219 fulcrumed on the stud, and this lever is connected by means of a link 220 with a slide block 221 which is guided in a housing 221^a on the end plate. This block is provided with a stud 221^b which is fitted to a vertical slot 222 in the proximate plunger bar 198, the end plate 204 being appropriately slotted, as at 222^a, for the free passage and guidance of the stud. The arrangement of the plunger slot 222 is such that the stud 221^b is free from the motion 10 of the plunger 198 until the end of the slot is reached, whereupon the link 220 is carried a predetermined distance by the movement of the plunger. This lost motion occurs during each stroke of the plunger, and as a 15 result a short throw of the link 220 and rock-lever 219 in time with the last portion of movement of the plunger 198 is effected, the pawl on the rock-lever thus intermittently turning the ratchet-wheel 214 and 20 accomplishing the operation of the presser plate 212. It is to be noted that each alternate ratchet impulse causes it to press the pressure plate against the wide strips, thus 25 keeping them away from the plunger 198 and preventing a wide strip from being driven down, and that each intervening impulse permits the plate to be forced back out of the way and a strip to be positioned in the path of the plunger 198 for delivery thereby 30 to the mouth of the temporary holder, as 35 above described.

The temporary holder herein illustrated is an intermittently-rotatable peripherally pocketed wheel 223, the pockets 224 of 40 which are adapted to be brought successively into alignment with the match-book chambers, as indicated in Figs. 24 and 25. In Fig. 24 a pocket is represented in position to receive the match books, and in Fig. 45 25 the partitioned rows of match books are indicated as delivered to the pocket. The wheel is mounted to rotate, preferably through ball bearings, upon a fixed annular structure 225 which is secured by a bracket 50 to the bed-plate 69; intermittent rotation being imparted to the wheel through a Geneva stop movement in order to advance the wheel pocket-by-pocket and lock it firmly at the end of each movement. One 55 member of the Geneva movement, indicated at 226 is integral with the pocket wheel, and the other or cam member 227 is fast on a shaft 228 journaled in a bearing on one side of the structure 225. The shaft 60 228 is equipped with a bevel gear 230 which meshes with a similar gear 231 on the upper end of a vertical shaft 232, the lower end of the latter bearing a bevel gear 233 in mesh with a gear 234 on the shaft 162 65 previously described, whereby motion is

transmitted from the latter to the shaft 228 and the two shafts are concurrently and correspondingly rotated. (See Figs. 2 and 29). In each dwell of the pocketed wheel 223 (Figs. 28, 29 and 30) the contents of 70 the lowermost pocket 224 are transferred therefrom to an underlying box or carton 235 by means of a vertically reciprocating plunger head 236 under which each of the pockets passes in succession. This plunger 75 head is fitted to slide in vertical guides 237 on the ends of the bearing structure 225, and is operatively connected by means of a rod 238 with one arm of a bell-crank lever 239 which is fulcrumed to a bracket on the 80 side of said structure. The other arm of the lever is connected by a pin or roll 240 with the groove of a face cam 241 on the shaft 228 which carries the Geneva movement cam 227. The two cams 241, 227 are 85 so arranged in relation to each other that the cam 241 is operative during the idle dwell of the Geneva movement, and the converse. The pockets of the temporary holder as they leave the packing station pass 90 upward, and hence the ends of the match books contained in the pockets can be readily inspected during their travel to the box discharging station. In order to avoid any liability of the books accidentally falling 95 out during their downward travel to the discharging station a segmental guard plate 242 is preferably supported adjacent their rotary path. As a still further safe-guard against the accidental egress of the books 100 at the bottom of the wheel, yielding supporting ledges 243 are arranged to extend just underneath the books contained in the lower pocket of the wheel in position to be acted upon by the plunger 236. These 105 ledges comprise plates pivoted to a suitably-disposed open frame 244 beneath the pocket wheel so as to open downward. The plates are normally held in raised position by springs 245 against the action of which they 110 are forced downward by the pressure of the match-books while the latter are being ejected from the pocket. The plates when swung downward enter the underlying box 115 in a manner to expand the opposing sides of the latter and thus serve as guides to conduct the books into the box. The boxes are successively fed into position to receive the match books ejected from the pocket wheel. As the contents of two pockets are required 120 to fill a box, the box is maintained in position to receive first two partitioned rows of books with a wide partition strip thereon and then two partitioned rows of books without the wide partition. The filled box 125 is then removed and an empty box positioned to receive the contents of the next two successive pockets of the wheel.

The mechanism for periodically feeding the boxes to and removing them from the 130

packing station will now be considered, reference being had more especially to Figs. 28 to 32, inclusive. 246 designates a carrier wheel comprising four equally spaced rectangular chambers 247, each of which is of appropriate size to receive and hold a box. These chambers are open through and through, and they are formed in an integral body which is fixed to a shaft 247^a journaled in bearings in the main frame. The carrier wheel is intermittently impelled to make one-quarter rotation with each second pocket movement of the pocketed wheel 223. This is effected through a gear train between the wheel 223 and the shaft 247^a of the carrier wheel, in which gear train is included an appropriate Geneva stop movement. The gear train comprises a gear rim 248 affixed to one side of the pocketed wheel; a gear wheel 249 in mesh with said gear rim, supported on a suitably-disposed stud shaft 250; a gear 251 mounted on a lower stud shaft 252 bearing a gear 253 having two oppositely-disposed series of teeth with intervening blank spaces 253^a, and a gear wheel 254 on the shaft 247^a. The gears 251, 254 constitute the Geneva stop, the latter being provided at intervals with laterally-disposed peripheral stop blocks 255 which successively co-act with segments 256 laterally of the blank surfaces of the gear 251 in order to lock the latter intermittently. The gear 253 is provided with suitably-disposed blocks 257 which co-act with the blocks 255 to perform the function of starters. (See Figs. 30, 31 and 32.) By the mechanism just described the box carrier 246 is actuated once for each two pocket movements of the pocketed wheel 223, and hence each box chamber containing an empty box 235, mouth upward, is so positioned that the contents of two pockets in succession, are delivered to the box.

It is to be noted that in the first discharge from the pocketed wheel by the plunger 236, two partitioned rows of match books with a wide partition strip thereon are depressed into the subjacent box 235 to a distance of an inch, say, below the top of the box and left there; but in the second discharge two rows of partitioned books, without a wide strip, are depressed into the said box so as to press down the opposing first charge to the bottom of the box and thus completely fill the latter. Thereupon the plunger 236 pushes the filled box slightly farther into the open chamber and upon a follower 258 within the chamber. There is a similar follower, (258) in each chamber, the opposite followers being rigidly coupled by rods 259 so as to be movable as a unit. Within the hollow body of the wheel structure is a circular spring 260 which encircles the shaft and is arranged yieldingly to support the followers when they are in inward position. (See Fig. 28.)

When the two vertically-movable followers 258 are forced downward the lower follower is automatically engaged and held by the inwardly extending tooth of latch dog 261 which is pivoted to a bracket 262 on the 70 main frame. The dog is held normally in locking position by a spring 263 secured thereto and to the bracket. Adjustment of the dog to regulate the engagement of the tooth on the follower may be nicely effected 75 by means of a set-screw 264 fitted in the base of the main frame to take against a laterally-projecting toe 265 on the dog. The latch dog remains in engagement with the follower until a rotative impulse of the carrier wheel forces the follower free of and past the dog, against the action of the spring 263, whereupon the dog resumes its normal position for reengagement with the next succeeding depressed follower. The walls of 80 the box chambers are appropriately slotted, as at 266, for the free passage of the dog. The empty boxes 235 are successively delivered to the chambers before the latter pass to packing position, and as rapidly as 85 each empty box is delivered to a chamber the filled box is ejected from the diametrically-opposite chamber by the unitary movement of the pair of connected followers. The empty boxes are contained, one upon another, within a vertically-disposed magazine 267 which is supported upon the main frame in the vicinity of the carrier wheel 246. The lowermost box lies laterally adjacent the horizontal receiving chamber of the wheel 90 and in the path of a plunger 268 by which it is ejected from the magazine and positioned at the mouth of said chamber. This box is forced into said chamber by means of a plunger 269 which is mounted to reciprocate in a guide bracket 269' on the base 65. (See Figs. 2 and 31.) The plunger 268 is connected by means of a link 270 with one arm of a bell-crank lever 271 fulcrumed to a bracket on the base of the main frame, the other arm of which lever has a pin and slot connection 272 with a lever 273 pivoted on said base, and a similar connection 274 with a link 275 which is pivoted to the plunger 269. The lever 273 is connected by means of a pin or roll 275^a with the groove of a cam 276 on a shaft 277 which is suitably journaled in bearings in the base of the main frame. This shaft bears a sprocket wheel 278 which is connected by means of a chain 279 with a similar wheel 280 on the intermittently rotatable shaft 162 previously described. Thus the shaft 277 and its cam 276 are rotated concurrently with said shaft 162. (See Figs. 2 and 29.) The contour of the 115 cam 276 is such that the plungers 268, 269 are successively actuated, the plunger 268 moving a box from the magazine 267 to the path of the plunger 269 and the latter then driving the said box into the adjacent cham- 120 125 130 135 140 145 150 155 160 165 170 175 180

ber of the carrier wheel against the opposing follower 258 until the latter bears against and compresses the internal spring 260. At the same time the companion follower bears against the opposing, filled box and pushes it from the carrier wheel to and upon an off-bearing belt 281, or other suitable take-off. This belt 281 passes about a pulley 282 on a suitably-disposed shaft 283 bearing a sprocket wheel 284 which is connected with and driven by a similar wheel 285 on the shaft 162 by means of a chain 286. (See Fig. 2.)

I claim as my invention—

1. In a machine for packing match books and the like, the combination of a book-positioning member, means for intermittently feeding articles thereto, and means for oscillating said member, whereby in one stroke of the member the articles therein are positioned vertically with their heads pointing in one direction and in the next stroke the succeeding articles in said member are similarly positioned but with their larger or headed ends pointing in a reverse direction to those of the others.

2. In a machine for packing match books and the like, the combination of a book-positioning member, means for intermittently feeding articles thereto, and means for oscillating said member, whereby in one stroke of the member the articles therein are positioned vertically with their heads pointing in one direction and in the next stroke the succeeding articles in said member are similarly positioned but with their larger or headed ends pointing in a reverse direction to those of the others, together with means for ejecting the vertically-disposed articles from said member.

3. In a machine for packing match books and the like, the combination of a rotary positioning member having two diametrical intersecting chambers at right angles to each other, means for oscillating said head, and means for introducing an article to a chamber positioned to receive the same at the end of each oscillation of the head, whereby the successive articles are positioned with their larger or headed ends in opposite relation to each other.

4. In a machine for packing match books and the like, the combination of a rotary positioning member having two diametrical intersecting chambers at right angles to each other, means for oscillating said head, means for introducing an article to a chamber positioned to receive the same at the end of each oscillation of the head, whereby the successive articles are positioned with their larger or headed ends in opposite relation to each other, and means for ejecting from the said member the articles positioned thereby.

5. In a machine for packing match books and the like, the combination of a reverse

wheel, means including a reciprocating frame for successively feeding articles to said wheel, and connections between said frame and the wheel whereby the wheel is oscillated by the action of the frame.

70

6. In a machine for packing match books and the like, the combination of a reverse wheel, means for feeding successive pairs of articles thereto, means for actuating said wheel whereby the articles therein are carried to a vertical position with the larger or headed ends of successive pairs in opposite relation to each other, and means for ejecting from the wheel the succeeding pairs of articles thus positioned, said ejecting means being so constructed that one of each pair of articles is moved to a horizontal plane below that of its companion.

75

7. In a machine for packing match books and the like, the combination of means for feeding articles, means for receiving said articles and positioning them with their larger or headed ends in opposite relation to each other, means for ejecting the succeeding articles thus positioned, a chamber adjacent to which the said articles are delivered, and means for moving the articles progressively into said chamber.

80

8. In a machine for packing match books and the like, the combination of means for feeding articles in pairs, means for receiving succeeding pairs and positioning them with their larger or headed ends in opposite relation to each other, means for ejecting the succeeding pairs of articles thus positioned, said ejecting means being so constructed that one of each pair of articles is moved to a horizontal plane below that of its companion, chambers in said planes, and means whereby the articles adjacent said chambers are moved sidewise thereinto.

85

9. In a machine for packing match books and the like, assembling chambers, means for feeding pairs of articles in paths adjacent said chambers, means movable relatively to said paths whereby each pair of articles is halted at the mouths of the respective chambers, but single articles are permitted to escape, and means whereby each pair of articles is moved into the chambers.

90

10. In a machine for packing match books and the like, assembling chambers, article guides adjacent thereto, members movable into said guides at the mouths of the respective chambers, and connections, including a tension spring, between said members whereby they are free to swing as a unit, the action of the spring being such that when articles contained in the guides are in contact with the two members such articles are held in position at the mouths of the respective chambers, and means whereby such articles are moved into the respective chambers.

95

11. In a machine for packing match books and the like, assembling chambers, means for

100

120

125

130

- feeding pairs of articles in paths adjacent to the mouths of said chambers, dogs movable into the respective paths, crank arms on said dogs, parallel rods for the respective crank arms, a link connecting said rods, and a spring also connecting said rods.
12. In a machine for packing match books and the like, assembling chambers, means for feeding pairs of articles in paths adjacent to the mouths of said chambers, dogs movable in the respective paths, crank arms on said dogs, parallel rods for the respective crank arms, a link connecting said rods, a spring, and adjustable connection between the same and said rods.
13. In a machine for packing match books and the like, assembling chambers, means for feeding pairs of articles in paths adjacent to the mouths of said chambers and at right angles thereto, means movable relatively to said paths whereby each pair of articles is halted at the mouths of the respective chambers but single articles permitted to escape, plungers movable across said paths and longitudinally of said chambers, and means for actuating said plungers.
14. In a machine for packing match books and the like, an assembling chamber, means for progressively feeding articles thereto, a back-stop for said articles movable longitudinally of the chamber, and means whereby said stop is automatically drawn backward when a predetermined number of books have been assembled in the chamber.
15. In a machine for packing match books and the like, an assembling chamber, means for progressively feeding articles thereto, a back-stop for said articles movable longitudinally of the chamber, means, including a spring connection, whereby said stop is maintained yieldingly against the leading end of a row of books in said chamber, and means whereby said stop is automatically drawn backward when a predetermined number of books have been assembled in the chamber.
16. In a machine for packing match books and the like, an assembling chamber, means for progressively feeding articles thereto, a back-stop for said articles movable longitudinally of the chamber, and means movable transversely of said chamber to eject therefrom a predetermined number of books assembled in said chamber.
17. In a machine for packing match books and the like, an assembling chamber, means for progressively feeding articles thereto, a back-stop for said articles movable longitudinally of and within said chamber, means whereby said stop is automatically drawn backward when a predetermined number of books have been assembled in the chamber, and means movable transversely of said chamber to eject the said books therefrom.
18. In a machine for packing match books and the like, an assembling chamber, means for progressively feeding articles thereto, a back-stop for said articles movable longitudinally of and within said chamber, means for determining the extent of travel of said stop, including a rotary drum, connection between said drum and the stop, and a counting mechanism operatively connected with said drum, and ejecting means movable transversely of said chamber.
19. In a machine for packing match books and the like, an assembling chamber, means for progressively feeding articles thereto, a back-stop for said articles movable longitudinally of and within said chamber, means, including a spring for maintaining said stop yieldingly in forward position, a drum, a yielding connection between said drum and the stop, a counting mechanism, a crank-connection between said mechanism and the drum, and ejecting means movable transversely of said chamber.
20. In a machine for packing match books and the like, an assembling chamber, plunger mechanism, for progressively feeding articles thereto, a back-stop for said articles movable longitudinally of the chamber, a gear wheel, operative connection between said wheel and the back-stop, actuating gearing for said gear wheel, and means controlled by the plunger mechanism for determining the periods of operation of the said gear wheel.
21. In a machine for packing match books and the like, an assembling chamber, plunger mechanism for progressively feeding articles thereto, a back-stop for said articles movable longitudinally of the chamber, a mutilated gear wheel, operative connection between said wheel and the back-stop, actuating gearing for said gear wheel, a pin wheel, a counting segment, connected with said gear wheel, and means controlled by the plunger mechanism for periodically actuating said pin wheel.
22. In a machine for packing match books and the like, an assembling chamber, plunger mechanism for progressively feeding articles thereto, a back-stop for said articles movable longitudinally of the chamber, a mutilated gear wheel, operative connection between said wheel and the back-stop, actuating gearing for said gear wheel, a pin-wheel, a counting segment, connected with said gear wheel, and means controlled by the plunger mechanism for periodically actuating said pin wheel, together with a locking dog for said pin-wheel.
23. In a machine for packing match books and the like, assembling chambers, means for feeding pairs of articles in paths adjacent to the mouths of said chambers, plunger mechanism movable across said paths and longitudinally of said chambers to feed the opposing articles progressively into the latter,

a back-stop for said articles movable longitudinally of the chamber, a mutilated gear wheel, operative connection between said wheel and the back-stop, actuating gearing 5 for said gear wheel, and means controlled by the plunger mechanism for determining the periods of operation of the said gear wheel, said last-named means including devices which are rendered temporarily inoperative in the absence of a pair of books 10 positioned for entry into the chambers by the plunger mechanism.

24. In a machine for packing match books and the like, assembling chambers, means for 15 feeding pairs of articles in paths adjacent the mouths of said chambers, plunger mechanism movable across said paths and longitudinally of said chambers to feed the opposing articles progressively into the latter, 20 a back-stop for said articles movable longitudinally of the chamber, and means under the control of the plunger mechanism for determining the extent of movement of said stop within the chamber, said means being 25 temporarily inoperative in the absence of a pair of articles positioned for entry into the chambers by the plunger mechanism.

25. In a machine for packing match books and the like, an assembling chamber, means 30 for feeding articles in a path adjacent the mouth of said chamber, plunger mechanism movable across said path and longitudinally of said chamber, and means under the control of the plunger mechanism for determining 35 the quantity of articles assembled in said chamber.

26. In a machine for packing match books and the like, assembling chambers, means for 40 feeding pairs of articles in paths adjacent the mouths of said chambers, plunger mechanism movable across said paths and longitudinally of said chambers to feed the opposing articles progressively into the latter, and means under the control of the said 45 mechanism for determining the quantity of articles assembled in said chambers, said means being temporarily inoperative in the absence of a pair of articles positioned for entry into the chambers by the plunger 50 mechanism.

27. In a machine for packing match books and the like, assembling chambers, means for 55 feeding pairs of articles in paths adjacent the mouths of said chambers, plunger mechanism, including heads, movable across said paths and longitudinally of said chambers to feed the opposing articles progressively into the latter, pivoted members in 60 said heads, rock-shafts having projections in the path of said members, two vibratory bars, cam connections between said bars and the respective rock-shafts, a dog pivotally connected with and reciprocable by the plunger mechanism and guided in a path pre- 65 scribed by the said bars, and means under

the influence of said dog for counting and determining the quantity of books assembled in said chambers.

28. In a machine for packing match books and the like, superposed assembling chambers, means for assembling rows of articles therein, means for introducing a partition strip between said rows, and means for ejecting from the chambers the two rows and the interposed strip. 75

29. In a machine for packing match books and the like, superposed chambers having a partition between them, means for assembling rows of articles in said chambers, spaced clips on the under side of the partition, means for introducing a partition strip to said clips, and means for ejecting from the chambers the two rows and the said strip. 80

30. In a machine for packing match books and the like, superposed chambers, means for assembling rows of articles therein, means for introducing a partition strip between said rows, a pocketed temporary holder, and means for transferring said rows 90 and strip from the chambers to the holder. 85

31. In a machine for packing match books and the like, superposed chambers, means for assembling rows of articles therein, means for introducing a narrow partition strip between said rows, a pocketed temporary holder, means for transferring said rows and strip from the chambers to the holder, and means for introducing a wide 95 partition strip to the temporary holder. 100

32. In a machine for packing match books and the like, superposed chambers, means for assembling rows of articles therein, means for introducing a narrow partition strip between said rows, a temporary holder having successive pockets therein, means for transferring associated rows and strip from the chambers to successive pockets of the holder, and means for introducing wide partition strips to alternate pockets of said 110 holder. 105

33. In a machine for packing match books and the like, superposed chambers, means for assembling rows of articles therein, means for introducing a partition strip between 115 said rows, a pocketed temporary holder, means for transferring said rows and strip from the chambers to the holder, means for supporting a box adjacent said holder, and means for transferring the associated rows 120 and strip from the holder to the box.

34. In a machine for packing match books and the like, superposed chambers, means for assembling rows of articles therein, means for introducing a narrow partition 125 strip between said rows, a temporary holder having successive pockets therein, means for transferring associated rows and strip from the chambers to successive pockets of the holder, means for introducing wide parti- 130

tion strips to alternate pockets of said holder, a carrier having successive box-holding pockets, and means for successively transferring the contents of two pockets of 5 the temporary holder to each box in said carrier.

35. In a machine for packing match books and the like, superposed chambers, means for assembling rows of articles therein, 10 means for introducing a narrow partition strip between said rows, a temporary holder having successive pockets therein, means for transferring associated rows and strips from the chambers to successive pockets of 15 the holder, means for introducing wide partition strips to alternate pockets of said holder, a carrier having successive box-holding pockets, and means for successively transferring the contents of two pockets of 20 the temporary holder to each box in said carrier, and means for ejecting the filled boxes from said carrier.

36. The combination of a pocketed temporary holder, means for progressively 25 moving the same, means for supplying rows of articles with an interposed partition strip to each pocket of the holder, a pocketed box-carrier, means for progressively moving said carrier in relation to the temporary 30 holder, and means for transferring associated articles and strips from the temporary holder to boxes in the box carrier.

37. The combination of a pocketed temporary holder, means for progressively 35 moving the same, means for supplying rows of articles with an interposed partition strip to each pocket of the holder, a pocketed box-carrier, means for progressively moving said carrier in relation to the temporary 40 holder, means for transferring associated articles and strips from the temporary holder to boxes in the box carrier, and means for discharging the filled boxes from 45 said carrier.

45. 38. The combination of a pocketed temporary holder, means for progressively moving the same, means for supplying rows of articles with an interposed partition strip to each pocket of the holder, a pocketed 50 box-carrier, means for progressively moving the same in relation to the temporary holder, means for transferring associated articles and strips from the temporary

holder to boxes in the box carrier, and means for also supplying wide partition 55 strips to the said boxes.

39. The combination of a pocketed temporary holder, means for progressively moving the same, means for supplying two rows of articles with an interposed partition strip to each pocket of the holder, a pocketed box-carrier, means for progressively moving said carrier in relation to the temporary holder, means for transferring associated articles and strips from the temporary 60 holder to boxes in the box-carrier, means for also supplying wide partition strips to the said boxes, and means for discharging the filled boxes from said carrier. 65

40. The combination of a pocketed temporary holder, means for progressively moving the same, means for supplying rows of articles with an interposed partition strip to each pocket of the holder, a pocketed box-carrier, means for progressively moving 70 said carrier to a position to present a box to the contents of two successive pockets of the temporary holder, means for transferring the associated articles and strips from the successive holders to the box, and means 75 whereby a wide partition strip is associated with the contents of alternate pockets of the temporary holder. 80

41. The combination of a pocketed temporary holder, means for progressively moving the same, means for supplying rows of articles with an interposed partition strip to each pocket of the holder, a pocketed box carrier, means for progressively moving said carrier to a position to present a box to the 85 contents of two successive pockets of the temporary holder, means for transferring the associated articles and strips from the successive holders to the box, means whereby a wide partition strip is associated with the 90 contents of alternate pockets of the temporary holder, and means for discharging the 95 filled boxes from said carrier.

Signed at Detroit, in the county of Wayne, and State of Michigan, this fourth day of April A. D. 1914.
